Primary Examiner — Nathaniel D. Buckner(74) *Attorney, Agent, or Firm* — Alexander R. Schlee; Schlee IP International, PC(57) **CLAIM**

The ornamental design for a housing for cable connectors, as shown and described.

DESCRIPTION

FIG. 1 is a bottom view of a housing for cable connectors; FIG. 2 is a first left side view thereof; FIG. 3 is a second rear side view thereof; FIG. 4 is a third front side view thereof; FIG. 5 is a top view thereof; and, FIG. 6 is a top-front perspective view thereof.

The ghosted areas and features shown bounded by broken lines depict portions of the housing for cable connectors that form no part of the claimed design.

1 Claim, 6 Drawing Sheets(56)
